UNITED STATES PATENT OFFICE.

LINCOLN CLARK, OF PASADENA, CALIFORNIA.

APPARATUS FOR TREATING PETROLEUM.

1,418,621.

Specification of Letter Patent. Patented June 6, 1922.

Application filed March 14, 1918. Serial No. 222,733.

To all whom it may concern:

Be it known that I, LINCOLN CLARK, a citizen of the United States, residing at Pasadena, county of Los Angeles, and State 5 of California, have invented a certain new and useful Apparatus for Treating Petroleum, of which the following is a specification.

My invention relates to an apparatus for 10 treating oils, especially of the petroleum class, and it has for its objects to provide a simple and efficient means for obtaining by distillation, separation or conversion any of the various constituents of the oil or other 15 yields.

The invention has in view the treatment 20 of oil by intimate association with, and action of, a heated fluid, which for the purposes of this disclosure, may include a variety of gases, such as combustion gases or 25 any other that be found most suited for the particular needs; the maintenance of a continuous circulatory movement by such heated gases or fluids, and the recovery of 30 whatever products may be yielded during the process of circulation; and it has also in view the provision of a means for rendering stable the proportion of heating and converting fluid to the oil, for the essential 35 purpose of obtaining specific products from specific oils.

Reference to the accompanying drawing is made as showing one form of apparatus that may be used in carrying out the objects enumerated and others. Therein,

Fig. 1 is a sectional view of an apparatus 40 for carrying out my invention, showing the oil receiving and containing chamber, the movable shell, and the inlet for the heated fluid.

Fig. 2 is a fragmentary enlarged detail 45 showing a means for operating the inside shell and holding such shell in position of adjustment, and

Fig. 3 is an enlarged fragmentary section on line 3—3, Fig. 1.

The invention comprises a vertical chamber 1, suitably supported and its lower end disposed within a fire box 2, for heating the 50 outside of the chamber 1 for a definite extent of its length, as hereinafter appearing. The bottom of the chamber is preferably that of a hollow inverted truncated cone 3, centrally within which is supported a deflecting member 4, arranged in line with

the outlet end of a heated fluid conducting pipe 5.

Leading from the truncated cone 3, is a pipe 6, through which solids or other residual and foreign matters formed during the 60 process of treatment, may be extracted, a gate valve 7 serving to keep the oil confined within the chamber during action of the heated fluid on the oil.

Within the chamber 1, is adjustably suspended a shell or other hollow body 8, diametrically smaller than the chamber 1, to provide a circumferential space or passageway B, and terminating in a truncated cone 9, the aforesaid pipe 5 disposed centrally of said shell or body 8 and of the opening in said cone, and having its end normally in the same horizontal plane as the cone 9, which as stated, is adjustably held and movable relatively to the end of 70 the pipe 5, by any suitable means, as eccentric 10, keyed on a shaft 11, and carrying suspension rods 12, which are pivotally attached to said shell or body 8.

At a desirable point above the cone 9 and 75 within the shell or body 8, may be disposed a foraminous sheet or screen 13, for preventing the passage of any solid, semi-solid, plastic or other substances and keeping 80 clear the space between the pipe 5 and cone 9. Through a suitable pipe 14, oil to be treated is introduced into the shell 8, the oil eventually flowing into and filling part 85 of the chamber 1, as presently pointed out.

Resultant products are taken off from the 90 chamber through a vapor line 15, for subsequent treatment.

In carrying out the process generally, the valve 7 is closed and oil delivered into the chamber 1, through pipe 14, either in the 95 form of a spray or a fine stream, or in any event in sufficient quantity to maintain at all times a definite level within the shell 8, the level always being within the heat zone of the fire box 2 during the treatment of 100 the oil.

The oil, which may be preheated by the fire in the fire box 2, as required by the nature and character of the hydrocarbon, is thereupon subjected to direct action of 105 heated gases the temperature of which for specific oils, ranges in accordance with the results desired, from about 80° F. to about 1200° F. and higher. These gases are introduced into the oil at a point below the 110

heat zone of the fire box 2, and, striking the deflector 4, are forced upwardly in the annular space B between the shell 8 and chamber 1, causing the oil to be carried upwardly therewith in said space to and above the top of the shell, whereupon it gravitates into the shell, and hence the oil is in continuous circulation during the treatment. Such circulation scours the walls of the chamber 10 and shell of any deposit lodging thereon as a result of the conversion of the oil, consequently a steady and even heat may be had during the entire process of treatment, a circumstance tending to the preservation 15 of the apparatus and economy of heat.

The steadily increasing heat required in ordinary stills, due to coke or other carbonaceous formation on the bottom thereof, is the cause of their speedy disintegration 20 and final destruction, but a condition of this character is wholly precluded in this apparatus.

Whatever free carbon may be formed in the course of the treatment of the oil, precipitates below the heat zone or that zone of the chamber which is not agitated by the gases, and asphaltic products that may deposit on the screen 13 are readily and quickly dissolved by the hot circulating oil.

30 The heated gases which escape to the top of the apparatus after traveling upwardly with the oil, may pass off through the pipe 15, with any products converted during the treatment.

35 On account of the different temperatures and other conditions that must be observed in respect of the treatment of variously constituted oils, a definite statement of temperature, velocity of travel of the oil and other 40 conditions, can only be made in respect of a specific oil, and obviously the conditions under which one class of oil may be treated successfully would not apply to other classes.

45 Destructive distillation of asphaltic residuums, i. e. residuums of distillation or fractionation, begins about 350° F. and continues until coke formation, about from 1000° F. to 1200° F., the initial points of destructive distillation and final points of coke formation 50 varying within the limits given according to the oil. Consequently asphaltic residuums of say 14 gravity passing through the apparatus, begin to be destructively distilled at about 350° F., such distillation or 55 cracking continuing until conversion into low boiling point products is complete or nearly so, which occurs at about from 600° F. to 900° F.

60 Destructive distillation or cracking alone is not purposed by this invention. Crude oil, with all of its fractions, may be distilled with as much facility as topped oils or residuums, and hence the temperature for such practice may begin for the very low boiling 65 point liquids at as low as 80° F.

In the treatment of all oils or its products, it is necessary that a proper proportion of heated gas and oil in the heat zone be maintained to govern the velocity of the oil past the heated surfaces and thereby to keep 70 clean the walls of the shell and chamber. This proportion or relationship of oil to gas is regulated by the relative position of the nozzle or pipe 5, to the outlet from the shell 8.

75 Obviously a prolonged subjection of residuums or oil products will bring about a conversion of them by destructive distillation or cracking; in much the same manner as by energetic treatment with higher heats. 80 However, the scouring action under slow moving heat conditions would be less complete and the time of treatment extended to periods which would make such a process un-commercial.

85 It is apparent that the operation of the still may be conducted under a pressure, where conditions so require, as for instance, where an oil is treated that is volatile at say 600° F. or 650° F., but whose cracking point 90 is say 900° F. or 950° F. or higher. In such event, pressure from external gases is maintained to bring about a pressure within the still and effect a destructive distillation at the higher temperature, the value 15' on the 95 vapor line 15 being partially closed during such subjection to pressure.

90 The original apparatus with which demonstrations have been made had outer shells of 12 inches diameter and 36 inches high, 10 and an inner shell 16 inches high, 8 inches in diameter with a space between the shells of two inches. The heating fluid pipe ranges from a quarter to three-eighths, with one-half inch diameter vapor outlet, one inch 10 residue outlet with cones of 60 degrees.

95 A subsequent still had an outer shell with a diameter of 36 inches and a height of 16 feet. The external heated area is seven feet high, the total area being approximately 16 1 square feet. The inner shell is six feet high with an annular space of one and one-half inches. The diameter of the heated fluid pipe is two inches and that of the vapor outlet six inches. The angle of the cones is 1 sixty degrees. The opening outlet of the cone of the inner cylinder is four and one-half inches. The amount of heated fluid was based on 400 feet of free air per minute at 1 70° Fahrenheit.

1 In operating the heating fluids I have topped oil at a vapor temperature of eighty degrees. The entraining property of the fluid assists in distillation at lower degrees than ordinarily.

1 The temperature of the fluid pipe runs from 100 to 1800° F. I have topped oil at varying pressures up to 110 pounds. The operating pressure in the still is no greater than the pressure on the fluid. I have 1

cracked heavy hydrocarbon down to coke at a final vapor temperature of 680° at no pressure. I have also cracked heavy carbon vapors at a temperature of 1187° and a 5 pressure of 65 pounds and have recovered lubricating stock vapors at a temperature of 780° using steam for heating fluid, and have operated the apparatus with heat from the fire box; also with heat only in the heating 10 fluid, and with both, I have operated using combustion gases and oil vapors as in the process set forth in my application No. 242-, 108, June 26, 1918, now pending. Oil in this 15 still acts as a medium to filter carbon and is also heated by such fluids resulting from the process in my before named application. Circulation of oil in the annular space is from one to fifty times a minute dependent of the character of the oil treated. The heat 20 pressure in my still is not greater than that on the heating fluid.

What I claim, is:—

1. An apparatus for fractionating oils or 25 treating residuums, comprising a furnace, a chamber vertically disposed therein, a shell within said chamber diametrically smaller than said chamber to form an annular space, a pipe extending centrally of said shell to supply an oil heating fluid, means in said 30 chamber and in line with the outlet of said pipe to deflect the heated fluid and cause it to pass upwardly between the shell and chamber, and means for adjusting the shell 35 relatively to said pipe to regulate the proportion of oil to the heated fluid.

2. An apparatus for fractionating oils or 40 treating residuums, comprising a furnace, a chamber disposed therein having its lower end extended below the heat zone of the furnace, a shell suspended within said chamber and diametrically smaller than said chamber to provide an annular passageway, said shell formed with a conical end, a heated 45 gas conducting pipe extending centrally of the shell, a deflector in said chamber and disposed in line with the opening of said pipe, and a valved vapor line leading from said chamber.

3. An apparatus for fractionating oils or

treating residuums, comprising a furnace, a 50 chamber disposed for part of its length within said furnace and its lower end extended below the heat zone of said furnace, a diametrically smaller hollow body within said chamber formed with a conical end, and 55 means to supply a heated fluid to heat the oil.

4. An apparatus for fractionating oil or 60 treating residuums, comprising a furnace, a chamber disposed therein for part of its length and its lower end extended below the heat zone of the furnace, a heated fluid supplying conduit central of said chamber, a concentric hollow body suspended within said chamber and adjustable relatively to 65 said conduit, a deflecting means for the fluid, and a vapor pipe on said chamber.

5. An apparatus for fractionating oils or 70 treating residuums, comprising a furnace, a chamber disposed for part of its length within said furnace and its lower end below the heat zone of the furnace, a heated fluid conducting pipe central of said chamber, a concentric hollow body adjustably suspended within said chamber and formed with a 75 conical end partly extending below the heat zone of the furnace, a screen within said hollow body, a means in said chamber to deflect the heated fluid and cause it to pass upwardly between said chamber and hollow 80 body, and a valved vapor line on said chamber.

6. An apparatus for fractionating oils or 85 treating residuums, comprising a chamber having a deflecting means in the bottom thereof, a shell suspended therein having a tapering end, and a heated fluid conducting pipe extending centrally of said shell, said shell terminating above the bottom of said chamber to provide a quiet zone for the liquid 90 while the upper zones thereof are circulated by the heated fluid.

In testimony whereof I have set my hand in the presence of two witnesses.

LINCOLN CLARK.
